UNITED STATES PATENT OFFICE

ROBERT POWELL, OF CINCINNATI, OHIO, ASSIGNOR TO THE NATIONAL PEELER COMPANY, OF CINCINNATI, OHIO, A CORPORATION OF OHIO.

PEELER.

954,047.

Specification of Letters Patent.

Patented Apr. 5, 1910.

Application filed March 29, 1909. Serial No. 486,393.

To all whom it may concern:

It is known that I, ROBERT POWELL, a citizen of the United States, residing at Cincinnati, in the county of Hamilton and State of Ohio, have invented certain new and useful Improvements in Peelers, of which the following is a specification.

My invention relates to peelers and washers, the object being to provide a more efficient machine of this character of simple construction, whereby liability of derangement and inconvenience in cleaning and adjustment of the parts are reduced to a minimum.

15 My invention consists in a cylindrical casing and a support therefor, constituting a drain and an inlet for a water supply for the casing, a disk rotatable in a horizontal plane within the casing, and means for rotating 20 the disk, a grater removably supported on the disk, a grater removably supported on the interior concave wall of the cylindrical casing, and an outlet for the vegetables from the casing.

25 My invention also consists in the additional parts and the combination and arrangement of the above named parts and these additional parts as will hereinafter be more fully described and claimed.

30 In the drawings: Figure 1 is a vertical section on the line $z-z$ of Fig. 4. Fig. 2 is a plan view of the part of the machine adjacent to the spout, the cover being removed. Fig. 3 is a detail perspective view of the 35 coupling that fits into the lower end of the tubular support. Fig. 4 is partly a plan view and partly a section on the line $y-y$ of Fig. 1, the disk and pinion being shown in plan, and part of the grater on the disk being broken away to illustrate the construction of the disk. Fig. 5 is a section of part 40 of a machine embodying a modification of the driving mechanism, the section being taken on a line corresponding to the line $x-x$ of Fig. 4 and part of the bearing and support therefor being shown in elevation.

45 Fig. 6 is a section of part of a machine embodying another modification of the driving mechanism, the section being taken on a line corresponding to the line $y-y$ of Fig. 1, and the part of the disk and the driving mechanism being shown in plan. Fig. 7 is a cross section through part of the disk on a line corresponding to the line $z-z$ of Fig. 4,

showing the manner of removably securing 55 the grater to the disk. Fig. 8 is a detail of the clip for securing the grater to the disk. Fig. 9 is a section of part of one of the graters, enlarged, and more clearly illustrating the formation of the burs thereon. 60 Fig. 10 is a detail perspective view of the grater for the inner concave wall of the casing. Fig. 11 is a detail perspective view of the door. Fig. 12 is a detail perspective view of one of the cleats for holding the 65 door and grater in position. Fig. 13 is a detail perspective view of a cleat of modified construction. Fig. 14 is a detail perspective view of the lug for holding the nozzle on the upward extension of the hub of the 70 disk. Fig. 15 is a detail perspective view of the nozzle. Fig. 16 is a detail perspective view of part of the disk, part of the spindle which extends through the hub of the disk and part of the nozzle in position on the hub 75 of the disk, around the spindle. Fig. 17 is a detail perspective view of the head which fits into the upper end of the tubular support with its spindle. Fig. 18 is a general perspective view of my improved peeler. 80

As illustrated, and as I prefer to embody my invention, the casing 1 is of cylindrical formation having its convex wall formed of a sheet 2, supported at its upper and lower edges, respectively, by hoops 3 and 4, and has 85 a conical bottom 5 converging to a tubular support 6, to which said bottom is rigidly secured with its joint therewith rendered water tight. At one side of the casing an opening is provided in the convex wall 90 thereof to form an outlet 7 which is provided with a spout 8 of suitable formation secured to the hoops 3 and 4 and to the sheet 2 of the casing. As shown, the hoop 3 continues around over the outlet 7 and behind 95 this hoop 3 a door 9 is mounted to slide vertically upward to open the outlet or downward to close it. This door is supported at the sides by cleats 10, which are secured to the inner concave wall of the casing and 100 have lips 11 taking over the parts of the door 9 near its vertical edges. This door 9 is provided with a flange 12 to afford a handle for operating the door. The cleats 10 also have lips 13 on their other sides, and a 105 removable grater 14 is adapted to fit closely against the inner concave wall of the casing therearound with its ends under these lips

13 of the cleats 10. This grater 14 consists in a long sheet provided with a series of burs 15 formed by perforating it in the well known manner of constructing graters from 5 metal sheets, as is best shown in Fig. 9 of the drawings. This sheet is slid into the casing vertically from the top with its burs 15 presented inwardly of the casing, being just long enough to spring closely against 10 the wall of the casing when its ends are held under the lips 13 of the cleats 10. The door 9 is provided with a grater 14' having similar burs 15, this grater being permanently secured to the door and terminates close to 15 the lips 11 on the cleats 10 which overlap the door. It will thus be seen that the grater 14 may be most conveniently withdrawn and inserted, thereby allowing the adjacent parts of the grater and the wall of the casing to 20 be cleaned and dried thoroughly, and allowing the grater, when it is worn out, to be replaced conveniently.

The cover 16 is frusto-conical in shape and fits into the top of the casing after the 25 manner of sheet metal lids, its smaller end 17 being up, and this end being open to conveniently admit the vegetables to be peeled. The adjacent part of this cover 16, preferably, is cut away to fit around the vertically 30 slidable door 9, and permit the free operation of the door when the cover 16 is in place on the casing.

The tubular support 6 extends above its juncture with the conical bottom 5 of the 35 casing to about the height of the lower part of the hoop 4 of the casing, and is provided with a series of openings 18 in its wall adjacent to its juncture with the bottom 5, these openings being so located and arranged that 40 water, carrying refuse from the vegetables, will readily pass from the bottom 5 of the casing through these openings 18 into the interior of the tubular support 6. The lower end of this tubular support 6 is rigidly secured to a suitable base 19 for the 45 machine, conical in general formation, with its smaller end up. Rigidly secured in the lower end of the tubular support 6, is a conical or funnel shaped coupling 20 with its 50 large end up and having a waste pipe 21 fitting into its lower smaller end. At one side of this waste pipe 21 the supply pipe 22 passes through the funnel shaped coupling 20, having a water tight joint therewith 55 at 23, and this supply pipe 22 passes upwardly and is deflected at 24 interiorly of the tubular support 6 so that it is brought into the center of said support. The upper end of this supply pipe 22 fits into a head 25 60 which has arms 26 extending radially therefrom in a horizontal direction, driven into the interior of the upper end of the tubular support 6. This head extends above the upper end of the tubular support 6, and is

reduced so that it has a spindle 27 and a 65 shoulder 28 at the beginning of said spindle.

An opening 29 extends entirely through the head and its reduced part which forms the spindle 27, communicating with the inlet pipe 22 at its lower end and forming an 70 outlet at its upper end. The disk 30 rotates on the spindle 27 in a horizontal plane, having a hub 31 extending above and below the disk and having radial ribs 32. This disk is provided with a heavy rim 30', and on the 75 periphery of this rim a series of teeth 33 are provided extending radially. Thus, the disk constitutes both a fly-wheel and a spur gear. A pinion 34 meshes with the teeth 33 of the disk at one side of the casing, preferably 80 at the side opposite to that on which the outlet 7 is provided, this pinion having a shaft 35 which extends vertically through the conical bottom of the casing at which point it is provided with a suitable gasket 85 36 to form a water tight joint between the shaft and the bottom of the casing. As shown, this shaft 35 forms part of an electric motor 37 which is mounted on a plate 38. However, it will be understood that 90 any other suitable motor or driving mechanism may be provided for the machine and supported on this plate 38. For supporting the plate 38, a clamp 39 takes around the tubular support 6 at any point between the 95 bottom 5 of the casing and the base 19, and has an arm 40 on which the plate 38 may be bolted. By having the clamp 39 thus adapted for adjustment vertically of the tubular support 6, the proper relative adjustment of the pinion 34 and disk 30 may be provided and maintained with great convenience, the clamp 39 being thoroughly rigid after the bolt 41, taking through its jaws, is tightened.

The hub 31 of the disk 30, where it extends above the disk, receives the nozzle 42 in the form of a tube with its upper end closed and its lower end open, this open lower end fitting over the spindle 27 where 110 it extends above the hub 31. This nozzle 42 is provided, near its upper closed end, with perforations 43 around it in its convex wall, these perforations being, preferably, provided in two series, the upper of which extend radially in a horizontal direction and the lower of which are inclined downward. For conveniently detachably securing this nozzle 42 on the upward extension of the hub 31 the lower end of the nozzle is provided with a slot 44 which extends upwardly parallel to the axis of the nozzle and then circumferentially thereof a short distance. The upward extension of the hub 31 is provided with a lug 45 extending vertically and then radially inwardly of the hub to take through the circumferentially extending part of the slot 44 when the lower

end of the nozzle rests against the top of the upper extension of the hub. Thus, in putting the nozzle in place it is only necessary to push it down onto the spindle 27, allowing the lug 45 to enter the vertical part of the slot 44, and then turn the nozzle so that the lug enters the circumferentially extending part of the slot.

The upper side of the disk 30 is left smooth to receive the grater 46, which is a circular sheet of diameter substantially equal to that of the disk, having a central opening 47 to fit over the upward extension of the hub 31 and adapted to lie flat on the flat upper surface of the disk. This grater has burs 15, like those on the grater 14 around the concave wall of the casing, and is secured to the disk 30 by means of clips 48 consisting in wires each with a horizontal part joining two vertical parts, the vertical parts being inserted downward through two openings 49 in the grater and through two openings 50 in the disk, the lower ends of the clips being bent under the lower surface of the disk. These clips may be of soft material so that they are conveniently bent and unbent to allow the grater to be placed in position or removed for cleaning and drying the adjacent surfaces of the grater 30 and the disk. Preferably, the grater 46 has a flange 46' to extend down over the periphery of the disk 30. The disk 30 is provided with a series of perforations 51 which allow drainage of water from under the grater. The disk 30 and its grater 46 are of somewhat less diameter than the interior diameter of the casing 1 so that an annular space 52 is left therearound adjacent to the wall of the casing. The parts are so proportioned that the concave grater 14 on the wall of the casing terminates substantially level with the upper surface of the circular grater 46 on the disk.

Thus constructed, vegetables, such as potatoes, or fruits of a similar nature, having skins to be removed, may be thrown into the casing through the open top 17 of the cover 16 onto the grater 46 on the disk 30, which is rotated, and the vegetables will be thrown outward by centrifugal force against the concave grater 14 on the wall of the casing and will rebound repeatedly with the result that after the operation of the machine for a short time the skins of the vegetables will be entirely removed by the continual abrasion of the burs 15 of the graters. Water being admitted through the inlet pipe 22 and through the opening 29, in the head 25 and its spindle 27, into the nozzle 42, this water will escape through the openings 43 in the nozzle and when under pressure will be projected with considerable force radially of the casing in a number of streams corresponding to the number

of openings 43 in the nozzle 42. The streams 65 from the upper series of openings will be directed in a horizontal direction, while those from the lower series will be directed downwardly. The result of such an arrangement of the streams of water from the nozzle, is that the horizontal streams strike the concave grater 14 near its upper termination, while the downwardly inclined streams strike it near its lower termination. These rotating streams thus striking the 75 stationary concave grater 14 are deflected backward onto the circular grater 46 and the particles of each stream striking with the particles of the other, due to the rotation of the nozzle, so distributes the water, 80 that both of the graters are continually washed in the most effective manner during the operation of the machine upon the vegetables. The skins of the vegetables, removed by the graters in small particles, are 85 thus washed down from the concave grater 14 and off from the horizontal circular grater 46 through the annular space 52 around the disk 30 and down along the bottom 5 of the casing through the openings 18 90 into the tubular support 6, and from there into the waste pipe 21 which may be connected with any suitable means for disposing of the refuse.

The supply pipe 22 may be connected 95 with suitable supply of water under pressure and may be provided with any desired means for controlling the flow of the water, which need not be herein shown or described.

The cover 16 of frusto-conical formation, as hereinbefore described, extending over the parts of the casing near its convex wall, prevents the splashing of the water out of the casing during the operation of the machine, but at the same time is always open for the ready insertion of the vegetables to be operated upon. When the vegetables have been operated upon for a sufficient length of time, as may be readily noted by inspection through the open top 17 of the cover of the casing, it is only necessary to slide the door 9 upward, opening the outlet 7, while a suitable receptacle is held under the spout 8, leaving the disk to rotate at full speed, 115 upon which the vegetables will be thrown out through the spout into the receptacle by the centrifugal force. The supply of water may be turned off before opening the door.

The pinion 34, as shown, is of greater diameter than the width of the annular space 52 around the disk 30, and, in order to make room for this pinion, the lower hoop 4 has a gap in it adjacent to the pinion, which is closed by a bulging plate 4', secured to the 125 ends of the hoop at the gap and holding the hoop together around the casing. As illustrated, this plate may have, formed integral

with it, part of the water tight joint around the shaft 35, where it extends through the bottom of the casing and is provided with the gasket 36, as hereinbefore mentioned.

5 As illustrated in Fig. 5 of the drawings, instead of providing the disk 30 with the radially extending teeth 33, it may have downwardly facing teeth 33' in such form that the disk constitutes a bevel gear, and a 10 bevel pinion 34' may be mounted on a horizontal shaft 35', this bevel pinion meshing with the teeth 33' of the disk. This shaft passes through the lower hoop 4 of the casing and has a water tight joint formed 15 therewith by means of the gasket 36'. A suitable bearing 53 is provided for the shaft outside the casing, mounted on a plate 38' of an arm 40' which may be secured to the tubular support of the casing by means of 20 a clamp similar to the clamp 39, as hereinbefore set forth. The shaft 35 may be the shaft of a suitable motor, or it may be otherwise suitably rotated.

Another modification of the driving mechanism consists in providing the periphery of the disk 30 with a series of teeth 33'' in such form that the disk constitutes a worm gear, and providing a worm 34'', which meshes with the teeth 33'' of the disk and is 25 mounted on a shaft 35'' extending tangentially through the wall of the casing and being part of a suitable motor 37''. This motor is mounted on a plate 38'' of an arm 40'' supported like the arm 40. Here the 30 hoop 4 of the casing is provided with a gap closed by a bulging plate 4'' to accommodate the worm 34'' and provide a bearing for the shaft 35'' where it passes tangentially through the wall of the casing in such 35 form that a suitable gasket 36'' may be provided around the shaft at this point to make a water tight joint.

It will be noted that with either the spur gear and pinion or the bevel gear and pinion considerable speed reduction from the motor to the disk may be attained, allowing the use of a small motor running at a high speed, which is conducive to economy in the first cost of the motor, as well as in the 40 maintenance of the device. With the use of the worm gearing, it will, of course, be understood that this speed reduction may be further increased with correspondingly increased advantages. In any instance, the 45 disk, when provided with the rim 30', will rotate steadily and insure smooth and even operative engagement of the gear teeth meshing at its periphery. Thus, this disk, performing its primary function of carrying the grater 46, constitutes part of the simple driving mechanism comprised by it and the pinion in mesh with its teeth and also the fly-wheel of the machine, all of 50 which is entirely inclosed in the cylindrical

casing, leaving no rapidly moving parts exposed, as may best be noted by referring to Fig. 18 of the drawings.

Having fully described my invention, what I claim as new and desire to secure by Letters Patent is:

1. In a peeler, having a casing and a disk rotatable therein, a central tubular support for the casing constituting a drain and being the entire support for the machine, and an inlet for the water supply for the casing 75 within said central tubular support, substantially as and for the purposes herein set forth.

2. In a peeler, a cylindrical casing having a conical bottom, and a disk rotatable in a horizontal plane within the casing, a central tubular drain support for the casing extending above the bottom thereof and provided with drain openings, and being the entire support for the machine, and a head on the 80 support forming a bearing for the disk and having an inlet for a water supply through said tubular drain support, substantially as and for the purposes herein set forth.

3. In a peeler, a cylindrical casing having 90 a conical bottom, and a disk rotatable in a horizontal plane within the casing, a central tubular drain support for the casing extending above the bottom thereof and provided with drain openings, and a head on the support 95 forming a bearing for the disk and having an inlet for a water supply through said tubular drain support, substantially as and for the purposes herein set forth.

4. In a peeler, having a casing and a disk 100 rotatable within the casing, a hub on the disk, a spindle for the hub to rotate on, an inlet for a water supply through the spindle, and a nozzle rotatably mounted on the hub of the rotary disk within the casing, substantially as and for the purposes herein set forth.

5. In a peeler, having a cylindrical casing and a disk rotatable in a horizontal plane therein, a central tubular drain support for 110 the casing extending vertically inside of the casing and carrying a bearing for the disk, a clamp embracing the central tubular drain support below the casing and adjustable thereon, a laterally extending arm on the 115 clamp, a motor mounted on the arm having a shaft extending vertically into the casing, said disk having teeth thereon whereby it constitutes a spur gear, and a spur pinion on the shaft of the motor in mesh with the 120 teeth on the disk, substantially as and for the purposes herein set forth.

6. In a peeler, having a casing, a central tubular support for the casing constituting a drain therefor, a water supply pipe extending through the central tubular drain support into the casing, a waste pipe, and a 125 coupling joining the waste pipe to the lower

end of the central tubular drain support, said water supply pipe passing through said coupling and forming a water tight joint therewith, substantially as and for the purposes herein set forth.

7. In a peeler, having a casing and a disk rotatable therein, a central tubular drain support for the casing extending up into the casing, a head having radial arms fitting into the upper end of the tubular support, a spindle extending upward from the head, the head and spindle having an opening continuous therethrough, a water supply connected to said opening, a hub on the disk fitting over and adapted to rotate on said spindle, an upward extension of the spindle, a nozzle fitting on the upward extension of the spindle and means for removably securing the nozzle to said hub to rotate therewith, substantially as and for the purposes herein set forth.

8. In a peeler, having a cylindrical casing and a disk adapted to rotate therein in a horizontal plane, the disk being of less diameter than the interior of the casing, whereby an annular space is left therearound within the casing, a conical bottom formed integral with the casing, a central drain support for the casing extending above the conical bottom, outlet openings in the central tubular drain support whereby refuse from above the disk may pass through said annular space to the conical bottom and from the conical bottom into the central tubular drain support, a waste connection to the central tubular drain support, a head mounted in the central tubular drain support above the outlet openings, a bearing for the disk on the head, and a nozzle mounted on the disk to rotate therewith, said head having an opening communicating with the nozzle and with a water supply pipe and adapted to discharge water therefrom in the form of spray, substantially as and for the purposes herein set forth.

9. In a peeler, having a cylindrical casing and a disk rotatable therein, a conical bottom on the casing, formed integral therewith, a central tubular drain support for the casing extending above the conical bottom, a head having radial arms fitting into the central tubular drain support at its upper end within the casing, a spindle on the head centrally thereof and of the cylindrical casing, said head and said spindle having an opening continuous therethrough, the disk being adapted to rotate on the spindle, a rotary nozzle communicating with the opening through the spindle and the head, a waste pipe, a coupling connecting the waste pipe with the lower end of the central tubular drain support centrally thereof, and a water supply pipe passing through the coupling at one side of the waste pipe.

and communicating with the opening in the head and the spindle, said water supply pipe being offset within said tubular support, substantially as and for the purposes herein set forth.

10. In a peeler, having a cylindrical casing and a disk rotatable therein, a spindle on which the disk rotates, a water supply opening through said spindle, a hub on the disk having an upward projection surrounding the spindle, a nozzle comprising a tube with its upper end closed and having its lower end fitting over the spindle, said nozzle being provided with perforations for the escape of water therefrom which is discharged in the form of spray, an axially and then circumferentially extending slot in the nozzle near its lower end, and a lug on the upward extension of the hub of the disk adapted to enter the axially extending part of the slot and then to enter the circumferentially extending part of the slot to hold said nozzle removably on said upward extension to rotate with said disk and prevent accidental disengagement therefrom, substantially as and for the purposes herein set forth.

11. In a peeler, having a cylindrical casing, and a disk rotatable therein in a horizontal plane, a stationary grater, and a grater adapted to rotate with the disk interiorly of the casing, a nozzle adapted to rotate with the disk, means for allowing the escape of water from said graters, said nozzle having a series of openings extending radially therein to allow the escape of water therefrom during the rotation thereof, which rotation causes the water to be directed outwardly from the center in the form of spray or drenching rain and to be thoroughly distributed to all parts of the interior of the machine, substantially as and for the purposes herein set forth.

12. In a peeler, having a cylindrical casing and a disk rotatable therein in a horizontal plane, a grater around the inner concave wall of the casing, a grater on the upper surface of the disk, a nozzle, consisting in a tube with its upper end closed, adapted to rotate with the disk, means for supplying water to the nozzle and means for allowing the escape of water from the disk and from the casing, said nozzle having a series of openings extending substantially horizontally to direct water against said grater on the concave wall of the casing near the top thereof, and a series of openings downwardly inclined to direct water against said grater near its bottom, the water thus directed against the grater being adapted to be deflected onto the grater on said disk, substantially as and for the purposes herein set forth.

13. In a peeler, having a cylindrical cas-

ing and a perforated disk rotatable therein in a horizontal plane, a hub having an upward extension on the disk, a rotary nozzle on the upward extension of the hub, means 5 for supplying water to the rotary nozzle, and a grater consisting in a circular perforated sheet provided with burs on its upper side and a central opening to fit over the up-

ward extension of the hub, said grater being formed of one piece and being removably secured on the upper side of said disk, substantially as and for the purposes herein set forth. 10
